[57] CLAIM

The ornamental design for a combination handset and stand telephone instrument, substantially as shown and described.

DESCRIPTION

FIG. 1 is a top plan view of a combination handset and stand telephone instrument showing our new design;
FIG. 2 is a front elevational view thereof;
FIG. 3 is a bottom plan view thereof;
FIG. 4 is a rear elevational view thereof;
FIG. 5 is a side elevational view thereof taken from the right side of FIG. 1;
FIG. 6 is a side elevational view thereof taken from the left side of FIG. 1;
FIG. 7 is a perspective view thereof; and
FIG. 8 is a bracket associated perspective view thereof showing (1) the handset inverted and spaced apart from the stand, and (2) the stand alone.
The showing of the cord in fragmentary form is for convenience of illustration.

FIG. 2

FIG. 1

FIG. 4

FIG. 3

FIG. 6

FIG. 5

FIG. 7

FIG. 8

UNITED STATES PATENT AND TRADEMARK OFFICE
CERTIFICATE OF CORRECTION

PATENT NO. : Des. 294,349

DATED : Feb. 23, 1988

INVENTOR(S) : Takashi OSHIMA, et al.

It is certified that error appears in the above-identified patent and that said Letters Patent is hereby corrected as shown below: On the title page

The following should be added to the Foreign Application Priority Data:

Dec. 3, 1985 [JP] 50357

Signed and Sealed this
Fifth Day of July, 1988

Attest:

DONALD J. QUIGG
